US0D1099388S

(12) **United States Design Patent** (10) **Patent No.:** **US D1,099,388 S**
(45) **Date of Patent:** **** Oct. 21, 2025**

(54) **CEILING FAN LIGHT KIT**

(71) Applicant: **Delta Electronics, Inc.**, Taoyuan (TW)

(72) Inventors: **Lung-Sheng Pan**, Taoyuan (TW);
Yen-Lin Chen, Taoyuan (TW);
Hsu-Fan Ai, Taoyuan (TW)

(73) Assignee: **Delta Electronics, Inc.**, Taoyuan (TW)

(**) Term: **15 Years**

(21) Appl. No.: **29/830,145**

(22) Filed: **Mar. 10, 2022**

(51) LOC (15) Cl. **26-05**

(52) U.S. Cl.

USPC **D26/59**; D26/81; D26/86

(57) **CLAIM**

The ornamental design for a ceiling fan light kit as shown and described.

DESCRIPTION

FIG. 1 is a perspective view of a ceiling fan light kit showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view of the ceiling fan light kit showing our new design where the ceiling fan light kit is in configuration of use.

The broken lines in the drawings depict environmental subject matter only and form no part of the claimed design.

1 Claim, 8 Drawing Sheets
